UNITED STATES PATENT OFFICE

2,437,716

HAND-OPERATED LOOM

Joseph Tiefenthal, West Babylon, N. Y.

Application May 2, 1945, Serial No. 591,451

6 Claims. (Cl. 139—29)

1

This invention refers to looms for weaving textile yarn, leather threads and the like and more particularly to hand-operated looms.

It is one of the objects of this invention to provide a simple and sturdy portable loom structure, which is light in weight, necessitates only a reduced and relatively small space and is collapsible for the purpose of storing or conveniently transporting the loom from place to place.

It is another object of the invention to provide a hand loom adapted for school and domestic use, as well as for use in the industry for pattern and fancy weaving purposes and for preparing specimens.

It is a further object of the invention to provide a hand loom including a reed, the latter being freely operable and changeable in its position relatively to the frame of the loom for the purpose of producing various thread surfaces and thread tensions.

Still another object of the invention is to provide means for adjusting and modifying the width and length of the loom structure, as well as of the beams.

A still further object of this invention is to provide a hand loom affording speedy and easy change of the weft thread relatively to the warp threads, enabling various weaving methods and facilitating the arrangement of the operating elements within a convenient distance from the front of the loom.

Yet, another object of this invention is accomplished by the provision of an inexpensive and effective reed structure which may also be employed for beating up the weft although it is not attached to the loom frame, but is readily replaceable by another suitable reed for obtaining different sizes and kinds (coarse or fine) of woven goods on the same loom; said other reed may be made shorter or longer than that which is replaced and without affecting or changing the frame structure of the collapsible loom.

Still, a further object of this invention is to provide simple means for varying the production of sheds between upper and lower series of warp threads although the same reed is employed for accommodating the warp threads.

Another object of this invention is to provide a collapsible weaving loom which is devoid of any complicated mechanical parts, such as harness, batten, heddle frame, which in conventional looms of the hand operated type are attached or linked to the frame thereof.

With these objects in view, the invention consists in certain features of novelty in the con-

2

struction, combination and arrangement of parts by which the aforesaid and several other objects, hereinafter set forth, are effected, all as fully described with reference to the accompanying drawings.

In the drawings:

Fig. 1 shows in perspective a hand-operated loom made in accordance with this invention.

Fig. 2 is a front-elevational view of a reed employed in the loom shown in Fig. 1.

Figs. 3, 4 and 5 illustrate schematically the positionings of the reed relatively to the hand loom shown in side elevation.

Fig. 6 shows a fragmentary, front-elevational view of a reed in modified form.

Fig. 7 is a cross-sectional view along line 7—7 in Fig. 6.

Fig. 8 shows a portion of one of the beams (partly in cross-section) employed in accordance with this invention.

Fig. 9 is a side-elevational view of an extension applicable to the beam shown in Fig. 8.

Fig. 10 is a front-elevational view, partly in section, of a lifting device employable in this invention.

Fig. 11 is a side-elevational view of the lifting device shown in Fig. 10 as connected to the frame (partly broken away) of the hand loom.

Referring now in greater detail to the attached drawings, there is disclosed in Fig. 1 a hand-operated and transportable loom 20 having the base frame bars 21, 22 and the standards 23, 24. As exemplified in Fig. 1 with respect to standard 24, these standards 23, 24 are linked as by means of hinges 25 to the respective bars 21, 22 so that these standards may be swung into vertical or upright and horizontal positions, respectively, as may be easily realized from Fig. 1. Thus, assembly and transportation of the collapsible loom 20 will be greatly facilitated.

Frame bars 21, 22 may be interconnected by transverse rods (not shown) frictionally and removably engaging suitable openings provided in walls of bars 21, 22 facing each other. Each of the bars 21, 22 are further provided with respective spaced apart sloping grooves or notches, 26, 27, 28 adapted to removably receive the yarn beam 30 and one or more guide rollers 29 if desired, whereby the frame work of the loom will be greatly stabilized.

Front or cloth beam 33 is removably inserted in slots 31, 32 provided in the forward ends of bars 21, 22.

Standards 23, 24 have the upper slots 34, 35 for

accommodating therein the ends of upper guide beam or carrier 36 which supports and guides the warp threads and further contributes to a more stable and rigid loom structure.

The end walls of standards 23, 24 are further provided with sloping slots 38 for engagement with the ends of a beam (not shown) which may be of a construction similar to that of beam 36. Standards 23, 24 carry, respectively, at their front end walls 39 displaceable holders or members 40, 40a for a purpose later described.

Members 40, 40a may slide, respectively, lengthwise of said end walls 39, 39a and may be actuated to this effect by screw devices 41, 41a extending beyond and above the standards 23, 24, respectively.

As shown in greater detail and on an enlarged scale in Figs. 10 and 11, front wall 39a of standard 24 has a recess 42a through which extends threaded rod 43a. Rod 43a threadedly engages spaced sleeve members 44, 45 forming parts of holder or supporting member 40a. One end 46 of rod 43a is seated in a suitable bearing 47 of standard 24 while the other end 48 of rod 43a projects beyond standard 24 to terminate into a handle 49. Since holder 40a is laterally guided between walls 50, 50a of recess 42a, it will be easily understood that upon actuation of screw device 41a by means of handle 49 holder or supporting member 40a may be displaced lengthwise of standard 24 and within recess 42a. It is further to be observed that screw device 41 as applied to and built in standard 23 is of a construction identical to that of the screw device 41a just described, so that it is not deemed necessary to explicitly explain screw device 41 whose function corresponds otherwise to that of device 41a.

Lifting devices 51, 52 consisting, respectively, of screw devices 40, 41 and 40a, 41a are employed to limit or vary the lift or throw of the reed device 53 about to be described hereafter, and further to vary the sheds of the upper and lower series of warp threads accommodated in the reed.

On the top surface of frame bars 21, 22 there are provided elongated abutment members 54, 55, respectively, which may be displaceably affixed to said bars, if desired.

Reed 53 may be made from stamped metal, wire or any suitable material, such as plastic or plastic composition and consists of a frame 56 having the transverse upper bar 57 and transverse lower bar 58. Bar 58 terminates into lateral extensions or handles 59 and 60 which are preferably offset with respect to bar 58.

Between bars 57 and 58 there extend, in this instance, a plurality of U-shaped wire elements 61, 62, 61a, 62a; etc. Element 61 is secured to bar 58, whereas element 62 is affixed to bar 57. U-shaped elements 61, 62 are so disposed with respect to each other that they present an elongated loop 63 whose upper and lower boundaries 64, 65 are formed by the bends of U-shaped elements 61, 62, respectively. Similarly, elements 61a, 62a provide therebetween loop 63a. Between loops 63, 63a, there is formed a slot 66 extending between the adjacent legs 67, 68 of elements 61, 62 and legs 67a, 68a of elements 61a, 62a.

In order to reinforce the reed structure, a longitudinal bar 69 may extend transversely there-to and parallel with transverse bar 57 to which elements 62, 62a, etc., are affixed as by brazing or soldering. It will be further observed that the space obtained between bar or rod 69 and bar 57 may be utilized to receive one or more filling

warps whereby the design of the resulting woven textile material may be modified.

In Fig. 2 there are designated warp threads 70, 70a, 70b within respective slots 66d, 66e, 66f, whereas warp threads 71, 71a are threaded through 63e and 63f. 72 is a filling thread indicated in its position in one of the slots provided between transverse bars 57 and 69.

Figs. 3 to 5 illustrate various positions and the manner of operating the reed 53 with respect to the loom frame. As it is known in the art, the warp threads 71, 71a, etc., and 70, 70a, etc., which are preferably of different color, thickness and shape are passed from the yarn beam 39 and guide beam 36 through the series of slots 63 and 66, respectively, and lead further over front or cloth beam 33 and one or more guide rollers 29, if desired. Reed 53 will be first placed on the top surface of holding members 40, 40a, respectively, whereby the warp threads passing through the series of slots 63 and those passing through slots 66 will be spread apart to facilitate the passage of the weft thread 80 supported by shuttle 81. Reed 53 is then moved by the hands of an operator grasping the handles 59, 60, toward the front of cloth beam 33 and when reed 53 is then placed on the surface of abutment members 54, 55 (Fig. 4), the warp threads 70, 71 are crossed to facilitate the passage of shuttle 81 in direction opposite to that indicated in the position of Fig. 3. Reed 53 is then further moved to the forward ends 54a, 55a of the abutment members 54, 55 and then swung forward toward cloth beam 33 to bring about tension of and even displacement 35 between the weft threads relatively to the warp threads, whereby a woven piece of textile material 100 is obtained.

Reed 53 may be further utilized to forwardly move the cloth piece 100 in the direction of cloth beam 33.

Although in Figs. 3 to 5, inclusive, two different series of warp threads 70, 71 are shown, it is well understood that thread 72 (Fig. 2) may be employed in addition to the series of threads 70, 71 to bring about variations of design.

Fig. 6 indicates a modification of the reed or heddle board designated by numeral 90 which, in this instance, is made from a plastic material or plastic composition, such as known in the trade 50 as "Bakelite," "Lucite," etc. Reed 90 is provided with a series of evenly spaced apart, elongated slots 91, 92, 93, 94, etc. Between adjacent slots 91 and 92, 92 and 93, 93 and 94 there extend a series of elongated slots 95, also in equidistance 55 from each other. A further row of equidistantly arranged slots 96 is disposed in a plane above slots 91-94 and slots series 95. The latter series of slots 96 substantially corresponds to slots provided in reed 53 and positioned between the cross bar 57 and transverse rod 69 (Fig. 2) whereas slots 91-94 substantially correspond to the series of elongated slots 66, 66a, 66b, etc. and rows of slots 95 are identical with slots 63, 63a, 63b, etc. of the reed shown in Fig. 2.

65 The handles 97 form lateral extensions of the lower part 98 of the heddle board or reed 90.

A reed of this type is inexpensive to manufacture, can be easily replaced or exchanged and since it is light in weight facilitates easy and effective operation.

70 The loom according to this invention may be used for different types of weaving systems and can be readily adjusted to different widths of woven fabrics by using beams and guide rollers 75 of the type shown in Figs. 8 and 9.

As can be seen from Fig. 8, the ends of guide beam 30 may be made longer by extension pieces 101, 102, according to the desired width of the loom, without changing the bars and standards forming the frame of the loom. If the beam requires the extensions 101, 102, the latter is coupled to the extension 101 by threaded engagement of a bolt 103 of extension 102 with threaded sleeve 104 inserted in the outer extremity of extension 101. Bolt 103 has a head 105 fixed and centered in hollow provided therefor in extension piece 102. Extension piece 102 has further a sleeve 106 (identical to sleeve 104) centered and inserted in the outer extremity of extension 102. Threaded sleeve 106 engages threaded bolt 107 which rests with its head 108 in grooves 26 of bars 21, 22, as can be easily realized from Fig. 1.

In the event that only extension 101 is needed for increasing the width of beam 30, the extension piece 102 may be disengaged from extension piece 101 by unscrewing bolt 103 from sleeve 104, and further by disengagement of bolt 107 from sleeve 106; bolt 107 being thereafter inserted into sleeve 104 of extension piece 101, whereby the width of beam 30 will be reduced by the length of extension piece 102.

In order to disengage extension piece 101 from beam 30, bolt 109 centrally fixed by means of head 110 on extension piece 101 is disengaged from sleeve 111 fitted into the end of beam 30.

Bolt 107—108 is then brought into engagement with sleeve 111 whereby the total width of beam 30 is further reduced by the length of extension piece 101.

It is well understood that the reed devices of Figs. 2 and 6 may be used for woven textile goods of a width smaller than that of the reed device itself. It is further to be noted that the upper surface of holding members 40, 40a forming platforms, may be equipped with grooves or abutment means to retain the reed in position on the platforms. Such abutment has been illustrated in Fig. 11, is designated by numeral 49b and consists of a bolt having an extension 49c which fits into one or more openings 40a (Fig. 1).

It is self understood that the loom otherwise functions and is operated in a conventional manner and as it is apparent from Fig. 1.

As can be seen from the above, there has been provided according to the present invention a collapsible loom which may be hand-operated by means of a freely movable reed in which the warp threads are accommodated, the loom comprising a frame including a pair of parallel side bars and a pair of standards, means hingedly connecting said standards to said side bars, respectively, whereby said standards may be moved substantially to the same plane as that of said side bars in collapsed condition of said loom, a front beam, a rear beam, said side bars being provided with a pair of openings in front of said standards and with a pair of openings rearwardly of said standards to receive in said openings, respectively, the ends of said front beam and of said rear beam, at least one guide roller, said standards being provided with a pair of openings to receive therein the ends of said guide roller, whereby said bars and said standards are braced by said front beam, said rear beam and said guide roller in operative position of said loom, an elongated member secured to the upper face of each side bar and positioned forwardly of said standards, said elongated members being each provided with an abutment edge, a movable platform supported by each standard and extending rearwardly of said mem-

bers, and respective means positioned on said standards for moving said platforms relatively to said members, the top surfaces of said platforms and said members forming respective rests for the reed of the loom during operation of said reed, said abutment edges forming a seat for said reed for beating up the warp threads.

As many possible embodiments may be made of the above invention, and as many changes might be made in the embodiments above set forth, it is to be understood that all matters hereinbefore disclosed or shown in the accompanying drawings are to be interpreted as illustrative and not in a limiting sense.

Having thus described the invention, what is claimed as new and desired to be secured by Letters Patent, is:

1. In a hand-operated loom having a frame including parallel side bars; a pair of standards, each standard being hinged to a respective side bar, a front beam, a yarn beam, one or more guide rollers extending transversely to said side bars, respective pairs of grooves provided in said side bars to accommodate therein the ends of said front beam, of said yarn beam and of said guide rollers, thereby enhancing stabilization of said frame, said side bars being each provided with an abutment member secured on the respective side bar and forwardly of said standards, and a platform displaceably accommodated in each standard, said platforms and said abutment members forming respective supports for the warp threads carrying reed which may be freely moved by the hands of an operator and independently of and relatively to said frame of the loom.

2. A hand-operated, collapsible loom comprising a frame including a pair of parallel side bars and a pair of standards, means hingedly connecting said standards to said side bars, respectively, whereby said standards may be moved substantially to the same plane as that of said side bars, a front beam, a warp thread beam, at least one guide roller between said front beam and said warp thread beam and extending transversely to said side bars, said side bars being provided with pairs of spaced apart openings to receive therein the ends of said front beam, of said warp thread beam, and of said guide roller, an abutment member secured on each side bar and positioned between said standards and said front beam, a lifting device accommodated in each standard, and means for moving said lifting devices, respectively, relatively to said standards, said devices and said abutment members forming respective rests for a reed to be freely moved by the hands of an operator and independently of and relatively to said frame of the loom, whereby the movements of the warp threads in upward and downward directions and passing through said reed and extending from said warp thread beam over said guide roller to said front beam may be varied relatively to said frame to thereby change the sheds of the warp threads for the introduction of the weft thread therebetween.

3. A hand-operated, collapsible loom comprising a frame including a pair of parallel side bars and a pair of standards, means hingedly connecting said standards to said side bars, respectively, whereby said standards may be moved substantially to the same plane as that of said side bars in collapsed condition of said loom, a front beam, a rear beam, said side bars being provided with pairs of spaced apart openings to receive therein the ends of said front beam and of said rear beam, at least one guide roller, said

standards being provided with at least one pair of openings to receive therein the ends of said guide roller to thereby brace said bars and said standards, an abutment member secured on the upper face of each side bar and positioned between said standards and said front beam, a movable platform supported by each standard, and means for moving said platforms, respectively, and relatively to said standards, said platforms and said abutment members forming respective rests for a reed to be freely moved by the hands of an operator and independently of and relatively to said frame of the loom, whereby the movements of the warp threads in upward and downward directions and passing through said reed and extending from said rear beam over said guide roller to said front beam may be varied to thereby change the sheds of the warp threads for the introduction of the weft thread therebetween.

4. A collapsible loom equipped with a reed for hand-operating the warp threads comprising a frame including a pair of parallel side bars and a pair of standards, means hingedly connecting said standards to said side bars, respectively, whereby said standards may be moved substantially to the same plane as that of said side bars in collapsed condition of said loom, a front beam, a rear beam, said side bars being provided with a pair of openings in front of said standards and with a pair of openings rearwardly of said standards to receive in said openings, respectively, the ends of said front beam and of said rear beam, at least one guide roller, said standards being provided with a pair of openings to receive therein the ends of said guide roller, whereby said bars and said standards are braced by said front beam, said rear beam and said guide roller in operative condition of said loom, a member secured on the upper face of each side bar and positioned forwardly of said standards, a movable platform supported by each standard and extending rearwardly of said members, and respective means for moving said platforms relatively to said standards, said platforms and said members forming respective rests for the reed of the loom during operation of said reed.

5. A collapsible loom equipped with a reed for hand-operating the warp threads comprising a frame including a pair of parallel side bars and a pair of standards, means hingedly connecting said standards to said side bars, respectively, whereby said standards may be moved substantially to the same plane as that of said side bars in collapsed condition of said loom, a front beam, a rear beam, said side bars being provided with a pair of openings in front of said standards and with a pair of openings rearwardly of said standards to receive in said openings, respectively, the ends of said front beam and of said rear beam, at

5 least one guide roller, said standards being provided with a pair of openings to receive therein the ends of said guide roller, whereby said bars and said standards are braced by said front beam, said rear beam and said guide roller in operative position of said loom, an elongated member secured to the upper face of each side bar and positioned forwardly of said standards, said elongated members being each provided with an 10 abutment edge, a movable platform supported by each standard and extending rearwardly of said members, and respective means positioned on said standards for moving said platforms relatively to said members, the top surfaces of said platforms and said members forming respective 15 rests for the reed of the loom during operation of said reed, said abutment edges forming a seat for said reed for beating up the warp threads.

6. A collapsible loom equipped with a reed for hand-operating the warp threads comprising a frame including a pair of parallel side bars and a pair of standards, means hingedly connecting said standards to said side bars, respectively, whereby said standards may be moved substantially to the same plane as that of said side bars in collapsed condition of said loom, a front beam, a rear beam, the ends of said front beam and of said rear beam being engageable with said side bars and for removal therefrom, at least one 20 guide roller provided with ends extending transversely of said standards and engageable therewith, whereby said bars are braced by said front beam and said rear beam and said standards are strutted by said guide roller in operative condition of said loom, a member including an abutment edge secured on the upper face of each side bar, and a platform supported by each standard and extending above and rearwardly of said members, said platforms and said members forming 25 respective rests for the reed of the loom during operation of said reed, said abutment edges forming a seat for said reed for beating up the warp threads.
